DÉCOLLETÉ BRASSIÈRE

William Rosenthal, Bayville, N. Y., assignor to
Maiden Form Brassiere Co., Inc., New York,
N. Y., a corporation of New York

Application July 2, 1948, Serial No. 36,622

3 Claims. (Cl. 2—42)

1

The present invention relates to improvements in brassières and more particularly to brassières of a décolleté type, that is adapted to be worn with dresses of the low-cut or décolleté type used principally for evening wear, and also with dresses having plunging necklines.

An important object of the invention is to provide a novel and advantageous form of brassière.

Another object of the invention is to provide a novel and advantageous type of brassière adapted to prevent the breasts of a wearer from slipping out of the breast pockets of the brassière.

Another object of the invention is to provide a novel and advantageous form of brassière adapted for wear under décolleté or low cut gowns.

Still another object of the invention is to provide a novel and advantageous décolleté brassière of inelastic material so constructed that when placed on a wearer, the breasts will be lifted upwardly and outwardly from a low cut central portion and the inner edges of the pockets will be drawn against the chest of the wearer to prevent escape of the breasts into the gap between the breast pockets.

A further object of the invention is to provide a novel and advantageous brassière of which the front is of inelastic material and shaping is provided for by gathering the fabric at certain parts.

According to a preferred embodiment of the present invention, the brassière is made of inelastic material except for short elastic parts or straps at the back equipped with suitable fastening devices, such as hooks and eyes. At the lower edge of the front of the brassière is a band which extends across the front of the body of the wearer and together with said front is connected to pieces which extend around the sides of the body, and partly across the back where their ends are connected together by means of the elastic back members or straps. From the middle point of said band, the inner edges of the breast pocket portions diverge upwardly to points at which are attached the forward ends of shoulder straps whose rearward ends are attached to the rear ends of the inelastic parts of the brassière. Just at the outside of each of the breast pocket sections is a stiffener extending from the lower edge to the upper edge of the brassière.

Breast pockets of low cut brassières in general use have no suitable provisions for keeping the breasts from working out of the breast pockets at the inner edges thereof. According to the present invention, the breasts are urged upwardly and outwardly by gathering the fabric in folds extending upwardly and outwardly from upwardly and inwardly inclined lines extending from the part of the brassière beneath the pockets to the inner edges of said pockets. The gathered or

2

shirred material is held against extension along these lines but may expand above the same. This expansion is accompanied by upward and outward pressure against the breasts.

Preferably the gathered effect is obtained by setting in a triangular shaping piece in the angle between the bottom of the brassière and the inner edge of a pocket. The gathered material of the breast pocket material is secured to the adjacent edge of the triangular piece. It is found that the purpose of the invention is served particularly well by this arrangement.

Other objects, features and advantages will appear upon consideration of the following detailed description and of the drawings, in which:

Fig. 1 is a perspective view illustrating a brassière embodying the present invention, as it appears on a wearer;

Fig. 2 is a view in rear elevation of the brassière as extended, and partially broken away to show underlying structure;

Fig. 3 is a larger scale view of a part of Fig. 1 illustrating details more clearly and partially broken away to show underlying structure;

Fig. 4 is a section taken along the line 4—4 of Fig. 3;

Fig. 5 is a section taken along the line 5—5 of Fig. 3; and

Fig. 6 is a view illustrating the triangular insert attached to the lower and inner edge of a breast pocket.

The drawings disclose a brassière embodying the present invention. As best shown in Figs. 1 and 2, the brassière comprises a right portion 10 and a left portion 10a which are symmetrically arranged on the opposite sides of a center line (not shown), the only exception to this symmetry residing in the different forms (right and left) of back straps 11 and 11a. Said right backstrap 11 comprises an elastic portion and a shorter inelastic portion provided at its inner face with fastening means such as a hook 12, and said left backstrap 11a comprises an elastic portion and an outer inelastic portion having at its outer face fastening means such as a plurality of eyes 12a.

The right portion 10 of the brassière comprises a breast pocket 13 including a piece 14 of fabric at the top of the pocket and a lower piece 15 of fabric which extends around the front and sides 50 of the breast of a wearer as well as beneath the same. The top piece 14 is four-sided or quadrilateral in shape and the two lower sides thereof are secured to the upper edge of piece 15, said upper edge being so shaped as to provide a forward projection of the pocket 13 with a point 16 at the vertex of the angle between the two lower sides or edges of the piece 14. Preferably pieces 14 and 15 are connected by openwork stitching.

At its outer or right edge said piece or member 15 is stitched to the adjacent edge of an inelastic fabric piece or member 17. At the seam

thus formed the edges are turned to the rear so that at the front the piece 17 overlies the piece 15. A covered stiffening member 18 is placed over the rear turned edges and secured in position by a strip of wide tape 33, fastened by lines of stitching 19.

Said fabric member 17 gradually decreases in height from its inner end to a point where it is attached to the rear end of a shoulder strap 20 and then decreases rapidly to a height just sufficient for attachment to back strap 11 through the spread ends of a loop 21 of elastic which constitutes this back strap. The forward end of said shoulder strap 20 is adjustably connected to a loop 22 secured to the high point of the top of member 14.

A very important feature of the invention resides in the construction at the lower and inner parts of the piece or member 15. Here the corner of piece 15 has been cut away and a triangular fabric piece or member 23 inserted for shaping purposes. Said member 23 is very close in shape to a right angle triangle, having one leg extending along the bottom of the brassière, that is substantially in alignment with the lower edge of part 15, and the other, somewhat shorter leg extending upwardly in alignment with the inner edge of the pocket. The side or edge 24 corresponding to the hypotenuse may be somewhat curved with its concave side directed upwardly and outwardly. Said edge 24 of said triangular piece is turned under and is attached to the adjacent gathered edge of the piece or member 15. At the inner face of the brassière and along said edge 24, there is a reinforcing strip or binding tape or binder 25 of which the edges are attached to the parts 15 and 23 by lines of stitching 26 (Fig. 3). It will be evident that the folds of the gathered material extend upwardly and outwardly from said edge 24, and that the edge 24 of the shaping insert 23 and the binding tape 25 maintain a fixed distance between a point on the inner edge of the breast pocket and the lower edge of part 15 of the brassière.

The edges of said part 10 above the bottom edge are reinforced by a binding strip or tape 32 which, if considered as starting at the lower right hand corner or base angle of triangular member 23 where it is tacked under the band 28, extends upwardly and inwardly to the other base angle member 23, where it is tacked under a strip of tape 27, which starts at the bottom central corner of member 17, runs outwardly and encircles the entire garment as far as the bottom central corner of member 17. The ends of the loop 22 and the rear end of shoulder strap 20 are secured between said binding strip or tape 27 and the pieces 14 and 17, respectively.

In the part 10a which engages the left side of the figure of the wearer, the parts are designated by adding *a* to the numerals representing corresponding parts in the right portion or part 10.

The two parts 10 and 10a are illustrated as completed and held together by a fabric strip 28 folded about its longitudinal medial line and with turned in edges engaging the lower edges of parts 23, 15, 23a and 15a, the ends of tape 32 and 32a, and the central point of tape 27 where it is folded back on itself, and secured thereto by a line of stitching 29. Said folded fabric strip 28 constitutes in effect a strap or band terminating at the junction of parts 15 and 17. The ends of the elastic in the loop 21 of the back strap 11 are secured against the outer ends of part 17 by

the peripheral binding tape 27, with two lines of stitching 31.

Referring to Figs. 1 and 3, it will be evident that the strip or band 28 will be held close to the body beneath the breast, the shoulder strap 20 will aid in keeping the inner edge of the breast pocket close to the body and the triangular shaping piece 23 will also be held close to the body. The gathered portion of member 15 will be expanded and the inner part of the breast pocket 13 may spread across and to the front of the inner edge of the pocket thus cooperating with the upward and outward lift of the gathered portion to hold the breast as desired and prevent it from slipping out of the pocket at its inner edge.

It should be understood that various changes may be made and that certain features may be used without others, without departing from the true scope and spirit of the invention.

What is claimed is:

1. A brassière comprising two breast pockets, side pieces adapted to extend to the back of the wearer, the pockets having inner edges separated from each other and diverging upwardly and outwardly, and a band attached along the lower edges of the pockets, each pocket comprising a diagonally-extending edge leading upwardly and inwardly from said band to the lower end of the pocket inner edge, and an inelastic triangular element having one side secured along said diagonally-extending pocket edge, a second side extending from said band upwardly to said lower end of the pocket inner edge, and a base secured 35 along said band.

2. A brassière as set forth in claim 1 wherein the material of each pocket is gathered in folds adjacent said diagonally-extending pocket edge, said folds being secured to said one side of said 40 triangular element and extending transversely thereto and upwardly and outwardly therefrom.

3. A brassière comprising two breast pockets, side pieces adapted to extend to the back of the wearer, the pockets having inner edges separated from each other and diverging upwardly and outwardly, and a band attached along the lower edge of the pockets, each pocket having a diagonally-extending reinforcing strip leading upwardly and inwardly from said band to the pocket inner edge, the material of each pocket being gathered in folds adjacent said diagonally-extending reinforcing strip, said folds being secured to said strip and extending in a direction transversely thereto and upwardly and outwardly therefrom, whereby the gathered material of the pocket is prevented from expanding in a direction along said folds but is free from limited expansion in a direction transverse to said folds.

WILLIAM ROSENTHAL.
